UNITED STATES PATENT OFFICE.

JOHN M. MOORE, OF WENA, ALABAMA.

DISTILLING APPARATUS.

SPECIFICATION forming part of Letters Patent No. 749,316, dated January 12, 1904.

Application filed February 25, 1903. Serial No. 145,056. (No model.)

To all whom it may concern:

Be it known that I, JOHN M. MOORE, a citizen of the United States, residing at Wena, in the county of Fayette and State of Alabama, 5 have invented a new and useful Distilling Apparatus, of which the following is a specification.

This invention relates to distilling apparatus, and has for its object to simplify and 10 cheapen the construction of such devices and likewise to improve the product and lessen the time and labor required to produce the desired results; and the invention consists in certain novel features of the construction, as 15 hereinafter shown and described, and specified in the claims following.

In the drawings illustrative of the invention, in which corresponding parts are denoted by like designating characters, Figure 20 1 is a longitudinal sectional elevation of the apparatus complete. Fig. 2 is a fragmentary view showing a portion of the condenser 14.

The improved apparatus consists of a receiver 10 for the "wort" or other material to 25 be treated and is preferably cylindrical in form and with a central open-ended flue 11 extending therethrough, as shown. Rising from the receiver near one end is a dome 12, communicating by its lower end with the interior of the receiver and connected thereto by a detachable joint 13, so that the dome may be detached and the receiver recharged 30 through the aperture connecting the receiver and dome. The dome 13 may be of any suitable construction, such as a telescopic or 35 "slip" joint, as shown, or other form which will be sufficiently tight to prevent the escape of vaporized material, while at the same time sufficiently yieldable to permit the ready separation of the parts when required.

Attached to the upper side of the shell of the receiver 10 is a condenser 14, the bottom 45 of the condenser being the portion of the shell of the receiver within the condenser, as shown, so that the heat radiating from the receiver will be readily imparted to the contents of the condenser.

Rising from the "head" of the dome 12 is 50 a conductor-pipe 15, extending to the condenser 14 at a slight incline and passing down-

ward through the head of the condenser and terminating near the bottom thereof, as shown at 16. Rising from the condenser 14 is another conductor-pipe 17, extending laterally to a "worm" 18 of the usual construction 55 immersed in a tank 19 of flowing cold water and having the usual discharge-pipe 20.

The receiver 10 will be provided with a waste draw-off 21, having a shut-off valve 22, while the condenser 14 is provided with a 60 draw-off 23, having a controlling-valve 24, the latter indicated only by dotted lines.

The dome 12 and condenser 14 are closed at their upper ends, and the condenser will be provided with an inlet 25, provided with a 65 valve 26, while the pipes 15 17 will likewise be provided, respectively, with valves 27 28, as shown, this inlet 25 providing means for the return of the "low-wines" to the condenser, as hereinafter explained.

The valve 26, provided in the inlet-pipe 25, serves the purpose of admitting the low-wines to the condenser after the volatilization of the contents of the receiver has been completed and prevents the escape into the outer air of 75 vapors from the condenser during the operation of the still. Valves 27 and 28 are provided to control the rate of passage of vapor from the receiver through the condenser into the worm, so that the vapor which passes 80 through the condenser and the worm may not exceed the condensing capacity of the worm.

The heat will be supplied to the apparatus within the end of the flue 11 farthest from the dome 12 and nearest to the condenser 14.

The volatile particles rising in the form of steam or gases pass over to the condenser 14 through the pipe 15 and are partly condensed therein and again subjected to the action of heat radiated from the hottest end of the receiver above the heating medium, as shown, resulting in the revaporation of the material and the discharge in the form of highly-heated vapor through the pipe 17 to the worm 18, where the final condensation takes place. By 95 this simple means the heating medium is utilized to perform the double function of a primary heating means for acting upon the material in the receiver 10 and, second, as a secondary heating means for producing the second 100

volatilization in the condenser 14. When the volatilization is completed in the receiver, the residuum is drawn off through the valve 22, while at the same time the material remaining in the condenser 14 is likewise drawn off through the valve 24. The material remaining in the receiver after volatilization is complete is waste, which is thrown away. The contents of the condenser at the end of the volatilization consists almost entirely of water, and this is also thrown away. The low-wines which escape from the worm during the final stages of the volatilization process are then returned to the condenser through the intake 25 to be again subjected to the action of the heat and the remaining particles of the "spirit" extracted therefrom. The receiver 10 is then recharged by the removal of the dome 12, as before described, and the operation repeated.

20 Any suitable heating medium may be employed within the flue 11; but an approved form of such a medium is shown, consisting of a tube open at the inner end and closed at the outer end and provided with a porous filling 25 or "wick" 29 and adapted to be inserted into the open end of the flue 11 farthest from the dome 12 and supported in position, as by legs 30. The wick member 29 will be provided with a metal clip 31, having a pin 32 extending therefrom through the rear head of the wick-tube and by which means the wick may be adjusted to regulate the flame. Rising from the wick-tube 28 is an oil-feed pipe 33, terminating in a supply-tank 34, having a valved 30 inlet 35, the feed-pipe likewise having a controlling-valve 36. By this simple means the wick member is supplied with oil to any required extent and the strength of the flame controlled, as will be readily understood. The 40 flame may thus be regulated to meet the required conditions and the requisite degree of heat uniformly imparted, with a resultant uniform and regular product. This form of burner possesses many advantages, as will be 45 obvious.

It will be noted that the flue 11 passes centrally through the shell 10, so that a large mass of the material remains at all times beneath the flue and the fire operating therein, 50 by which means the shell 10 is protected from the direct action of the fire and the vaporization produced by a less degree of heat, as the heat radiates into the mass of the material from all sides of the central flue and none of it is lost 55 by radiation into the walls of a furnace or exterior fire-chamber.

The whole device is very simple, compact, and efficient and may be enlarged or reduced in size, as required, to enable it to produce 60 any desired amount of distillate and will work with perfect satisfaction in connection with the largest or the smallest structure. It will

be found especially advantageous for portable or experimental purposes, as it can be constructed in small sizes and will not require 65 cumbersome or expensive attachments or co-operating machinery to enable it to be successfully operated. A comparatively large apparatus may be operated by one person of ordinary skill, as there are no cumbersome or complicated parts to manipulate or get out of order.

The parts may be of any suitable material, but will preferably be of sheet metal properly 75 coated and protected to resist the chemical action of the material being treated and will preferably be of the material generally employed in the construction of stills and similar apparatus.

Having thus described the invention, what 80 I claim is—

1. In a distilling apparatus, the combination of a horizontal cylindrical receiver having a single central flue of relatively large diameter extending therethrough longitudinally of the 85 receiver, a detachable dome mounted on the upper portion of the receiver adjacent to one end thereof and communicating with the interior of the receiver, a condenser mounted on the top of said receiver adjacent to the other 90 end thereof, the shell of the receiver forming the bottom of the condenser, a condensing-pipe leading from the top of said dome to said condenser and terminating within said condenser near the bottom thereof, an inlet-valve 95 and an outlet-valve associated with said condenser, a conductor-pipe leading laterally from the top of said condenser to a worm and a discharge-valve in the bottom of said receiver.

2. The combination in a distilling apparatus of a horizontal cylindrical receiver having a single central flue of relatively large diameter extending longitudinally through said receiver, a condenser mounted on top of said receiver near one end thereof, a flange mounted on top of said receiver near the other end thereof and surrounding an opening in said receiver, a removable dome fitted within said flange, a condenser-pipe rising from the top 105 of said dome and leading laterally to said condenser within which said pipe terminates near the bottom, inlet and outlet valves associated with said condenser, a conductor-pipe leading laterally from the top of said condenser 110 and a discharge-valve in the bottom of said receiver.

In testimony that I claim the foregoing as my own I have hereto affixed my signature in the presence of two witnesses.

JOHN M. MOORE.
